(57) **CLAIM**

The ornamental design for a dispenser housing, as shown and described.

DESCRIPTION

FIG. 1 is an isometric view of a top, front, and right side of an ornamental design for a dispenser housing;

FIG. 2 is a front elevational view of the housing of FIG. 1;

FIG. 3 is a rear elevational view of the housing of FIG. 1;

FIG. 4 is a right side elevational view of the housing of FIG. 1;

FIG. 5 is a left side elevational view of the housing of FIG. 1; and,

FIG. 6 is a top plan view of the housing of FIG. 1, a bottom plan view being a mirror image thereof.

The evenly weighted broken lines in figures are for the purpose of illustrating environmental structure and form no part of the claimed design. The dash-dot-dash-dot lines of the figures illustrate a symbolic break within the sidewalls of the claimed design and they represent a break in the length and the width. The appearance of any portion of the article between the break lines forms no part of the claimed design.

1 Claim, 3 Drawing Sheets
